(57) **CLAIM**

The ornamental design of a cell phone support, as shown and described.

DESCRIPTION

FIG. 1 is a front perspective view of my cell phone support, showing the novel cell phone support design.

FIG. 2 is a front elevation view of the cell phone support design.

FIG. 3 is a rear elevation view of the cell phone support design.

FIG. 4 is a side view, taken looking at the left side of the cell phone support.

FIG. 5 is a side view, taken looking at the right side of the cell phone support.

FIG. 6 is a top plan view of the cell phone support; and,

FIG. 7 is a bottom plan view of the cell phone support.

Those portions and features shown in broken lines are unclaimed subject matter.

The characteristic feature of the design resides in the cell phone support, namely, a transparent cell phone securing panel elastically mounted to a base.
